DESIGN FOR AN ICE CREAM CONE

Ernest A. Hamwi, St. Louis, Mo.

Application November 29, 1941, Serial No. 104,397

Term of patent 3½ years

To all whom it may concern:

Be it known that I, Ernest A. Hamwi, a citizen of the United States, residing at the city of St. Louis, State of Missouri, have invented a new, original, and ornamental Design for an Ice Cream Cone, of which the following is a specification, reference being made to the accompanying drawing, forming part thereof, in which—

Fig. 1 is an elevational view showing the open end of my new design for an ice cream cone.

Fig. 2 is an elevational view showing one side of my new design, the diametrically opposite side being a duplicate of that shown.

Fig. 3 is an elevational view showing another side of my new design, the diametrically opposite side being a duplicate of that shown.

I claim:

The ornamental design for an ice cream cone, as shown and described.

ERNEST A. HAMWI.
